Inventor:
John C. Stiles.

By Elliott & Ammen
Attorneys.

UNITED STATES PATENT OFFICE.

JOHN C. STILES, OF ST. LOUIS, MISSOURI.

HEEL CONSTRUCTION.

Application filed April 5, 1922. Serial No. 549,837.

To all whom it may concern:

Be it known that I, JOHN C. STILES, a citizen of the United States, residing in the city of St. Louis and State of Missouri, have 5 invented new and useful Improvements in Heel Construction, of which the following is a specification.

This invention relates to a heel construction for boots, shoes and slippers, and the 10 general object of the invention is to produce a simple construction including means for attaching a heel to the sole of the shoe which will give rigidity and prevent any possibility of lateral rocking of the heel with respect to the sole to which it is attached; also 15 to produce a heel construction which is inexpensive to produce in quantities and the parts of which are so related as to enable them to be readily assembled in securing the 20 heel to a shoe or slipper. The construction involves the use of a heel plate which is secured to the sole of the shoe and constructed to have the heel secured to it. One of the 25 special objects of my invention is to provide a seat or face on which the heel plate is supported effectively on the upper side of the heel and in such a way as to prevent any possibility of the heel rocking on the plate.

Further objects of the invention will appear hereinafter.

The invention consists in the novel features, and in the general combination of parts to be particularly described herein-after, all of which contribute to produce a 35 simple and efficient heel construction. A preferred embodiment of my invention will be particularly described in the following specification, while the broad scope of my invention will be pointed out in the appended claims.

In the drawing,

Figure 1 is a plan of a heel construction embodying my invention, that is, it shows the heel construction as it would appear 45 with the sole removed from above it;

Figure 2 is a vertical section through the heel construction taken on the line 2-2 of Figure 1 and indicating the sole and outline of the counter of the shoe in dotted lines;

Figure 3 is a plan of the heel or body piece of the heel construction, with the heel plate removed;

Figure 4 is a cross section taken on the line 4-4 of Figure 2, and particularly illustrating the means for supporting the heel plate in a transverse plane;

Figure 5 is a cross section taken on the line 5-5 of Figure 2;

Figure 6 is a bottom plan of the heel plate; and

Figure 7 is a side elevation of the heel plate.

In practicing my invention I provide a heel 1 which I prefer to construct of metal, and in order to give it lightness, I provide its upper part with a chamber 2 so that the heel presents an inclined rear wall 3 and a forwardly extending wall 4. This heel may have any desired shape to suit the prevailing styles. By reason of the chamber 2 the upper portion of the heel is in the form of a shell.

Supported on this heel I provide a heel plate 5 whose outline conforms substantially to the outline of the upper side of the heel. 75 In order to provide an effective support for the heel plate on the heel, I provide a transversely disposed seat 6 which is disposed at an intermediate point on the upper side of the heel. This seat is simply a face which is slightly dished in a transverse direction (see Figure 4). In the present instance I construct it in the form of a bridge cast integrally with the shell which constitutes the upper portion of the heel. The heel plate 5 80 is slightly dished so that it fits closely upon the transverse seat 6. If desired, of course, this seat could extend all the way back to the back edge of the heel, but I prefer to form the seat by means of a bridge because 85 this will leave a chamber 2^a at the rear edge of the heel which also reduces the weight of this part.

The upper portion of the heel is provided with a socket extending forwardly and inclining downwardly from a point behind the seat 6. I prefer to provide a pair of these sockets 7, 7 which extend downwardly in a direction substantially parallel with the rear inclined wall 3. The heel plate 5 is constructed with means such as openings 8 for the attachment of nails 9 to secure the heel plate to the rear portion of the sole 10 of the shoe. The heel plate is further provided with a pair of tongues 11 which may be struck integrally from it and which extend downwardly and forwardly, the construction being such that the sockets will operate to guide the tongues longitudinally through the sockets when the heel plate is forced down onto the seat 6. The heel plate preferably has a square cut forward end

12 which extends across the forward portion of the heel and which rests firmly upon this part of the heel which forms a seat 13 to support it (see Figure 5.) In this way it will be seen that the heel plate is firmly supported throughout its entire width, on the heel. After the heel plate and shoe have been attached to the heel by sliding the tongues into the sockets and firmly seating the plate as described, I then secure the heel 1 to the sole 10 by suitable means such as nails 14 which may be driven through three nail holes 15 provided at the forward edge of the heel. By reason of the fact that the tongues and sockets extend along a line passing under the seat it will be evident that the tongues engaging as they do the upper faces 16 of the sockets will effectually prevent any rocking movement of the plate in a transverse plane. That is to say, they will effectively hold the plate upon its seat 6. It will be evident that the only relative movement of the plate and heel would be that which would occur from an outward sliding movement of the tongues in the sockets, but such a sliding movement is effectually prevented by the nails or fastening devices 14. The upper faces 16 of the sockets 7 are preferably concave (see Figure 4) and the lower faces are curved to correspond with the curvature of the outer face of the heel. The tongues 11 are bent in a transverse plane so that they present their curved sides 17 uppermost. This transverse bend or channel shape which I give to each tongue gives it great strength and resiliency, and enables them to press tightly against the upper faces of the sockets. They, therefore, operate to hold the heel plate very snugly upon the heel plate 6. The slightly dished shape of the heel plate increases its stiffness and also enables its edges to conform more nicely to the edges of the shell which forms the upper part of the heel. The middle and forward portion of the heel plate may be punched out so as to form a large opening 18 which reduces the weight of the heel plate without reducing its necessary strength.

The features of construction of the heel 1 are such as to enable it to be readily produced complete as a die-casting. This enables the complete heel construction to be produced very economically.

It is understood that the embodiment of the invention described herein is only one of the many embodiments my invention may take, and I do not wish to be limited in the practice of my invention nor in my claims, to the particular embodiment set forth.

What I claim is:

1. In a heel construction, the combination of a heel, having a transversely disposed seat at an intermediate point on the upper side thereof with a socket extending

forwardly and inclining downwardly from a point behind the seat on a line passing under the seat, a heel-plate having a tongue extending forwardly and down into the socket, said heel-plate constructed to be secured to the heel portion of the sole of the shoe, resting upon said seat and supported thereby and having its forward end supported on the forward portion of the heel, and means for securing the forward portion of the heel to the sole. 75

2. In a heel construction, the combination of a heel having a transversely disposed seat at an intermediate point on the upper side thereof, and having a chamber extending down into its interior forward of said seat, and having a pair of sockets inclining downwardly from a point behind the seat on a line passing under the seat, a heel plate having a pair of tongues extending forwardly and down into the sockets, said heel-plate constructed to be secured to the heel portion of the sole of the shoe, resting upon the seat and supported thereby and having its forward end supported on the forward portion of the heel, and means for securing the forward portions of the heel plate and the heel to the sole. 80

3. In a heel construction, the combination of a heel having a transversely disposed bridge at an intermediate point on the upper side thereof and having a pair of sockets extending forwardly and inclining downwardly from the upper portion of the heel along a line extending under the bridge, a heel plate constructed to be secured to the heel portion of the sole of the shoe, resting upon said bridge and supported thereby having a pair of tongues extending forwardly and down into said sockets, and having its forward end supported on the forward portion of the heel, and means for securing the heel plate to the heel. 95

4. In a heel construction, the combination of a heel having a chamber formed in its upper side with an inclined rear wall and a forwardly projecting wall, and having an integral bridge extending transversely across the chamber over the inclined rear wall, said bridge having sockets, a heel plate constructed to be secured to the heel portion of the sole of the shoe, seating upon said bridge and supported thereby and having a pair of integral tongues fitting into the sockets under the bridge, means for securing the forward portion of the heel plate to the sole, and means for securing the forward portion of the heel to the sole. 105

5. In a heel construction, the combination of a heel having a chamber formed in its upper side with an inclined rear wall and a forwardly projecting wall, a bridge extending transversely across the chamber over the inclined rear wall and having a 110

pair of oppositely disposed sockets extending downwardly and forwardly adjacent to the rear wall, a heel plate constructed to be secured to the heel portion of the sole 5 of the shoe, resting upon said bridge and supported thereby, said heel plate having a pair of integral tongues extending downwardly into the sockets, said forwardly projecting wall engaging and supporting the 10 under side of the heel plate at the forward edge thereof.

6. In a heel construction, the combination of a heel having a transversely disposed seat at an intermediate point on the upper side

thereof, and having a socket extending forwardly and inclining downwardly, a heel plate having a tongue extending down into the socket constructed to be secured to the heel portion of the sole of the shoe, resting upon said seat and supported thereby, and having its forward end supported on the forward portion of the heel, and means for securing the forward portion of the heel to the sole.

In testimony whereof, I have hereunto set 25 my hand.

JOHN C. STILES.
